JOHN F. DUSTIN, OF FULTON, NEW YORK.

PICKER MECHANISM FOR LOOMS.

1,034,433.

Specification of Letters Patent.

Patented Aug. 6, 1912.

Application filed April 15, 1909. Serial No. 490,039.

To all whom it may concern:

Be it known that I, JOHN F. DUSTIN, a citizen of the United States of America, residing at Fulton, in the county of Oswego 5 and State of New York, have invented new and useful Improvements in Picker Mechanism for Looms, of which the following is a specification.

This invention relates to improvements in 10 picking devices for looms, the invention relating particularly to improvements in the construction of the sweep-stick, and in means of adjustment to regulate the throw of the picker-stick, all as hereinafter fully 15 described and pointed out in the claims, the invention being clearly illustrated in the accompanying drawings, in which,—

Figure 1 is a side elevation of a construction embodying the invention showing the 20 parts in one position. Fig. 2 is a like view showing the parts in a different position of adjustment. Fig. 3 is a plan view of the sweep-stick, picking-arm, and picker-stick, the upper end of the latter being broken off, 25 as is also the lower end of the picking-arm. Fig. 4 is an enlarged perspective view of a block of wood, fiber, or the like removably supported in the forward end of the sweep-stick. Fig. 5 is a side elevation of a picker- 30 arm and a part of the sweep-stick showing a modification of the construction illustrated in Figs. 1 and 2. Fig. 6 is a side elevation of a picker-arm and a part of the sweep-stick showing still another modification of the construction shown in Figs. 1 35 and 2.

Referring now to these drawings, *a* is the picking-arm; *b* the picker-stick, and *c* indicates, as a whole, the sweep-stick. A portion 40 of a shuttle is indicated by *d*,—*e* indicating conventionally a part of a shuttle box.

The picker-stick *b* Fig. 2 is pivotally supported on a bolt *f* in an arm *g* which is pivotally and adjustably supported, as shown in Fig. 2, on bolt *f* extending through a slot *h* of the frame of the loom, indicated by *k*, a bolt *h* passes through a slot *o* concentric with the bolt *f* for purposes of adjustment. 45 A second slot in said arm *g* (also concentric to the bolt *f*) is provided, and a second bolt may pass therethrough into said frame part. It is thus apparent that by loosening the bolt *h* the arm *g* may be adjusted relative to the 50 support *k* to effect, to a greater or less extent, the vertical adjustment of the end of

the sweep-stick *c* so as to shift the point of contact of the sweep-stick on the picker stick without affecting the adjustment, vertically, of said picker-stick. The slot in 60 member *k* is for the purpose of permitting an adjustment of the picker-stick *b* and the arm *g* relative to the member *k* in an obvious manner. To the free end of this arm *g* is pivoted the rigid sweep-stick support *q* the upper end of which preferably extends between the two sides of the sweep-stick *c* and is pivotally connected thereto by means of a bolt *r*. The supporting arm *q* will maintain a position of parallelism to the 70 picker-stick in all positions.

It is thus apparent, by a comparison of the position of the parts just described, as shown in Figs. 1 and 2, that a wide range of adjustment of the relation of the sweep-stick to the picker-stick is provided, and the swing of the picking arm being through a fixed arc, the throw of the shuttle may be thus regulated to a nicety. Still further means of adjustment are provided by making the sweep-stick adjustable longitudinally. Broadly, it is recognized that this is 75 not new, and, broadly, no claim is made herein therefor.

The sweep-stick consists of two parts *s* 80 and *t*, which are made of metal straps preferably, bent into the form of loops with parallel sides, the ends of one of said parts overlapping or being embraced by the ends of the other; said overlapping ends being 85 perforated with registering holes *v* whereby they may be clamped together, the clamping devices consisting of a clip *w* and a bolt *x* which passes through a hole in the clip *w*, and one of the holes *v* in the overlapping ends of the sweep-stick parts, the end of said clip *w* being provided with a 90 rectangularly disposed end which extends through another hole *v*; thus when the nut on the bolt *x* is tightened, the two parts of 95 the sweep-stick will be locked together in such a manner as to provide against all longitudinal strain to which it is subjected, and also against any sagging of the center which might take place if these two parts of the 100 sweep-stick were secured together only by means of the bolt *x*. At the free end of the part *s* of the sweep-stick is secured, in any suitable way, a pad of leather or the like at the point of contact with the picker-stick. 110 In the forward end of the part *t* of the sweep-stick a suitable pocket is provided to

receive a block 3 (shown in perspective in Fig. 4) which may be made of wood, fiber, rawhide, or any other suitable material. Preferably, this pocket is made of such form as to take a block having a tapering end, such as is shown in the drawing, the taper being such as would naturally cause the block to wedge tightly in the pocket while rendering it easily removable therefrom. 5 Such a pocket is readily formed by cutting a T-shaped blank from sheet metal, two arms 4 of which are bent around the outside of the forward end of said part *t* of the sweepstick, the other end of the blank being 10 formed to receive the narrow end of the wedge-shaped block 3. Any other method, however, of making a pocket in the end of the sweep-stick may be employed, it being 15 only essential that the rounded end 5 of the block be left so exposed that the similarly rounded end 6 of the picker-arm *a* may have a free bearing thereagainst.

For the purpose of supporting the forward end of the sweep-stick it is preferred 20 to construct the picking-arm with a spur 7 extending out under the forward end of the sweep-stick, the upper surface of the spur being made on a suitable curve to permit the sweep-stick to ride easily thereon 25 when the arm is in any position.

The block 3 takes the thrust of the picking-arm when the latter swings forward to throw the shuttle *d* and to take the thrust 30 of this arm when it swings back again, a second block of wood or other suitable material, (indicated by 8) is located between the sides of the part *t* of the sweep-stick just back of the curved end 6 of the picking-arm, said block 8 being secured in the 35 sweep-stick in any suitable manner, as for example by means of a pin 9 passing therethrough and through the sides of the sweep-stick. The edge of this block 8 against which the picking-arm bears is suitably 40 rounded to render the action of the parts as easy as possible, but the wear to which this block is subjected is not as great as that of the block 3.

If desired, the blocks 3 and 8 may be 45 made in one piece with an opening to receive the end of the picking-arm, but preferably the construction is as shown and described herein.

From the foregoing description it is seen 50 that provision has been made in this construction for the accurate adjustment of the throw of the picker-stick through a relatively wide range including as it does not only the adjustment of the arm *g* but also 55 the longitudinal adjustment of the sweep-stick, and means have also been provided for reducing to a minimum the wear of the parts of the sweep-stick at the point of their connection with the picking-arm, and also 60 for the quick renewal of these last-named

parts, it being possible to lift the end of the sweep-stick off of the end of the picking-arm and put in a new block 3 in a few moments.

What I claim, is: —

1. In a picker mechanism for looms, the combination of a picking stick, a sweep-stick having an opening in one end, a picking arm having a curved projection adapted to engage the under side of the forward end of the sweep-stick, the upper surface of the projecting portion being curved to permit the sweep-stick to ride freely thereon upon operation of the picking arm, a bearing block in said opening, the upper end of the picking arm extending into said opening adjacent said bearing block and adapted to shift the sweep-stick in opposite directions by engaging one end of said opening and said bearing block upon operation of the picking arm. 70

2. In a picker-mechanism for looms, the combination with a picker-stick, a picker-arm, a sweep-stick having an opening in one end, a pocket in the opening and having bendable fingers to removably secure the pocket to the sweep-stick and a bearing block in the pocket for engagement by the picker-arm, the picker-arm having a curved projection to support the front end of the sweep-stick and also having another curved 80 projection which engages said bearing-block when the picking-arm shifts the sweep-stick in one direction. 85

3. In a picker mechanism for looms, the combination of a picking-stick, a sweep-stick having an opening, a pocket disposed in said opening and provided with parts which embrace opposite sides of the opening to secure the pocket in the opening of the sweep-stick, a bearing block for the picking arm disposed in said pocket, and a picking arm having a curved projection which engages the under side of the sweep-stick to permit the latter to ride freely thereon upon operation of the picking arm, the upper end of the picking arm extending into said opening for engagement with the bearing block when the picking arm shifts the sweep-stick in one direction. 100

4. In a picker mechanism for looms in combination the frame work of the machine, a picker stick pivotally secured to the frame, a picking arm, a sweep-stick having connection with the picker stick, an arm secured on the pivot of the picker stick, said arm having a slot concentric with said pivot, a bolt passing through said slot, and a supporting stick secured to said arm and passing through the sweep-stick. 110

5. In a picker mechanism for looms, in combination, the frame work of the machine, a picker stick pivotally secured to the frame, a picking arm, a sweep-stick having connection with the picker stick, an arm secured on the pivot of the picker-stick, a 120

130

supporting stick secured to said arm at one side of the pivot and connected to the sweep-stick and an adjusting means on the other side of the pivot whereby the point at which 5 the sweep-stick connects with the picker stick can be changed.

6. In a picker mechanism for looms, in combination, the frame work of the machine, a picker stick pivotally secured to the frame, 10 means to adjust the picker stick in the frame comprising a bolt on which the picker stick is pivoted and a slot in the frame through which the bolt can be moved to various posi-

tions carrying the picker stick therewith, a picking arm, a sweep-stick having connection with the picker stick, an arm secured to said bolt, a supporting stick secured to said arm at one side of the bolt and connected to the sweep stick and an adjusting means on the other side of the pivot whereby 15 the point at which the sweep stick connects with the picker stick can be changed.
